UNITED STATES PATENT OFFICE.

ALBERT WANNER, JR., OF HOBOKEN, NEW JERSEY.

OPERA-CHAIR.

981,232.

Specification of Letters Patent. Patented Jan. 10, 1911.

Application filed February 21, 1910. Serial No. 544,960.

To all whom it may concern:

Be it known that I, ALBERT WANNER, Jr., a citizen of the United States, residing in Hoboken, Hudson county, and State of New Jersey, have invented a certain new and useful Improvement in Opera-Chairs; and I do hereby declare the following to be a full, clear, and exact description of the invention, such as will enable others skilled in the art

to which it appertains to make and use the same, reference being had to the accompanying drawings, and to letters of reference marked thereon, which form a part of this specification.

5 My object in and by the present invention is to improve chairs of the type employed in auditoriums and other public places principally in respect to reducing the cost of manufacture thereof while retaining them
20 neat, attractive and substantial in appearance, and in other respects, for instance, that, while they may be light in construction and therefore readily portable, they will be strong and durable; that they may be
25 adapted to occupy as little space as possible when not in use (their seats being then folded or swung into flatwise relation with the backs), affording free access to any chair in a row in passing between rows; that a
30 row of the chairs may be readily adapted to different curvatures according to a pre-determined seating plan; that different styles of backs may be utilized without materially altering the other parts of the chairs to
35 adapt them to them; that the individual width of the chairs may be varied, etc.

In an application filed of even date herewith I have described and claimed a chair comprising, with a back and back-leg structure and standards disposed forward thereof, a substantially U-shaped member having its end-portions projecting substantially forwardly and rigidly connecting the said standards and back and back-leg structure.

45 One salient feature of this invention consists in supporting a pivotally mounted seat when in the seating position by means of the forwardly projecting end-portions of the said member, preferably through the
50 medium of a bar or the like traversing the said end-portions. Another consists in a novel means for pivotally mounting the seat. Still another consists in a novel means co-operating with said member in connecting together the standards and the back and back-leg structure, such means preferably

affording arms for the chair and permitting changes in the transverse dimension of the chair and also serving in the formation of a unitary structure, comprising two or more 60 chairs, which if need be may be adjusted to suit different row curvatures.

In the accompanying drawings, the invention has been shown in connection with a group of two chairs forming a unitary structure, Figure 1 being a perspective view; Fig. 2 a horizontal sectional view taken in a plane above the seats; Fig. 3 a vertical sectional view, the seat being shown raised in full lines and partly lowered in dot-and-dash out-line; Fig. 4 a similar view, the seat being shown lowered in full lines and partly lowered in dot-and-dash out-line; Fig. 5 a front elevation of the pivotal mounting for the seat; Fig. 6 a vertical sectional 75 view of said mounting; and, Fig. 7 is a sectional view on line α — α of Fig. 1.

In the drawings, a designates the back and back-leg structures, b the seats, and c standards disposed forward of the said structures and each extending above the seating plane of the seat; the leg-portions of said structures and standards diverge downwardly to impart the desired stability to the frames of the chairs and may or may not be attached to the floor. It will be understood that different styles of back and back-leg structures may be employed.

The back and back-leg structure of each chair is rigidly connected with the corresponding standards in approximately the seating plane by means similar to that set forth in my co-pending application above referred to, the same being herein a substantially U-shaped member d having its 95 ends projecting forwardly, its rear portion being secured to the back and back-leg structure and its ends to the respective standards by screws e or the like. On the ends of this member rests a transverse support f which lends rigidity to the frame and serves to support the seat in its depressed position; this support, which may be a wooden bar, may be attached to the member d by screws g . As will hereinafter appear, the back portion of 100 said member serves as a support to sustain a certain link-connection whereby the seat is pivotally supported when in the idle or folded position.

To afford arms for the chairs, an inverted 110 L-shaped member h is attached by one leg i thereof (secured by screws or the like j) to

the back and back-leg structure, the other leg *h* projecting forwardly, said forwardly projecting leg and the standard being surmounted by the arm-proper *l* into which the standard may be doweled and which may be secured to said member by screws *m*. This construction lends stability and strength to the chair as a whole and affords a substantial and rigid brace as between the back and back-leg structure and each standard. The inner faces of the legs *i* of members *h* being rounded (Fig. 7) allows the positions of said members on their legs *i* as axes to be changed to vary the width of the chair.

Where the chairs are used two or more in a group, as shown in the drawings, a single standard is preferably used between each two chairs, the bar *f* is made long enough to traverse the end-portions of the members *d*, and a single arm-proper serves for two adjoining chairs, their two L-shaped members being attached to the common arm-proper. The row-curvature of the group may be varied according to the relative positions of the legs *k* of members *h* with respect to the common arm-proper.

The seat is supported as follows: A strap *n* is attached by screws *o* to the under side of the seat at the back thereof, extending transversely; its ends are upturned. A link connection between this strap and the back and back-leg support is afforded by the links *p* which are pivoted at *q* (by rivets or the like) to the ends of the strap and at *r* (by screws or the like) to the back and back-leg support. The disposition of the pivotal points *q* and *r* is such that when the seat is in the seating position, resting on the bar *f*, the links stand substantially vertically and when the seat is in its elevated position they rest on the support afforded by the back-portion of member *d*. In the seating position, the seat may be prevented from a tendency toward backward planiform movement both by the projection *s* (formed by the front wall of a notch *t* which is provided in the under side of the seat at each side thereof) abutting against the bar *f* and by the seat engaging the back, or by either of these expedients; the seat is kept from forward movement by the projection *s'* (at the back of each notch) engaging the back of bar *f*. Upon raising the seat the links stand with relation thereto at first substantially as they appear in Fig. 4. When the seat impinges against the back the pivotally connected seat and links buckle, the links swinging forward and downward until they come to rest on the back-portion of member *f*; this allows the seat to assume a flatwise relation with the back of the chair. In depressing the seat, it first moves pivotally around the points *q* until it engages the bar *f*; upon pressing downwardly

upon the forward portion of the seat a reverse buckling as between it and the links will follow until the notches in the seat coincide with bar *f*, whereupon further backward planiform movement of the seat will be stopped. It will be observed that, particularly in lowering the seat, its movements are accomplished in a manner well calculated to prevent undue noise and jar.

Having thus fully described my invention, what I claim as new and desire to secure by Letters Patent is:—

1. The combination, with a frame having a forward seat-supporting means, of a seat pivotally movable around an axis back of said supporting means upwardly out of, and downwardly into, supported relation to said supporting means, and a link connection pivoted to the frame on said axis and also to the seat on an axis parallel with the first axis, said link connection normally standing substantially upright when the seat is in the supported relation to the supporting means and being pivotally movable forwardly when the seat is raised, substantially as described. 90

2. The combination, with a frame having a forward seat-supporting means, of a seat pivotally movable around an axis back of said supporting means upwardly out of, and downwardly into, supported relation to said supporting means, and a link connection pivoted to the frame on said axis and also to the seat on an axis parallel with the first axis, said link connection normally standing substantially upright when the seat is in the supported relation to the supporting means and being pivotally movable forwardly when the seat is raised, said supporting means and seat interlocking with each other to 100 prevent planiform movement of the seat, substantially as described. 100

3. The combination, with a frame having a forward seat-supporting means, of a seat pivotally movable around an axis back of said supporting means upwardly out of, and downwardly into, supported relation to said supporting means, a link connection pivoted to the frame on said axis and also to the seat on an axis parallel with the first axis, said link connection normally standing substantially upright when the seat is in the supported relation to the supporting means and being pivotally movable forwardly when the seat is raised, and means, engageable by 110 the link connection, for limiting its forward pivotal movement, substantially as described. 115

4. The combination, with a frame, of a seat and a link connection connecting the seat with the frame and pivotally movable with respect to both on horizontal axes, said frame having means for supporting the seat when the latter is in its depressed position and also means, engageable by the connec- 125 130

tion, for limiting the pivotal movement of said connection, substantially as described.

5. The combination, with a frame, of a seat and a link connection connecting the seat with the frame and pivotally movable with respect to both on horizontal axes, said frame having means for supporting the seat when the latter is in its depressed position and also means, engageable by the connection, for limiting the forward pivotal movement of said connection, substantially as described.

6. The combination, with a frame having supports arranged one in advance of the other, a seat adapted to rest on the forward support when in its depressed position, and a link connection connecting the rear portion of the seat with the frame and pivotally movable with respect to both on horizontal axes, the rear support being disposed within the range of movement of said connection on its axis of movement in the frame in the forward direction, substantially as described.

5 7. The combination, with a frame, of a seat and a link connection connecting the rear portion of the seat with the frame and pivotally movable with respect to both on horizontal axes, said frame having means, 0 comprising a substantially U-shaped member having its ends projecting substantially forward, for supporting the seat when depressed and supporting said connection when the seat is raised, substantially as de- 35 scribed.

8. The combination, with a frame having a forward seat-supporting means, of a seat pivotally movable around an axis back of said supporting means upwardly out of, and 40 downwardly into, supported relation to said supporting means, a strap attached to said seat near the back thereof and having its ends upturned, and links pivoted to the frame on said axis and also to the upturned 45 ends of said strap, said links normally standing substantially upright when the seat is in the supported relation to the sup-

porting means and being pivotally movable forwardly when the seat is raised, substantially as described.

50 9. The combination, with the back and back-leg structure, the seat and standards arranged forward of said structure and projecting above the seating plane, of means for rigidly connecting said structure with each standard comprising substantially L-shaped members each having one leg thereof projecting forward and the other formed with a cross-sectionally round face secured against a vertical face of said structure, substantially as described.

60 10. The combination, with the back and back-leg structure, the seat and standards arranged forward of said structure and projecting above the seating plane, of substantially L-shaped members each having one leg thereof attached to said structure and the other projecting forwardly and an arm rigidly connecting each standard with the forwardly projecting leg of said member, substantially as described.

70 11. The combination, with back and back-leg structures arranged side by side, seats, and standards disposed forward of said structures and also arranged side by side, of substantially U-shaped members having their end-portions projecting forwardly and connecting said structures with the standards, the adjoining end-portions of adjoining members being attached to a common standard, and substantially L-shaped members rigidly connecting the back and back-leg structures with the standards above the first members, each two adjoining L-shaped members being connected to a common standard, substantially as described.

In testimony, that I claim the foregoing, I have hereunto set my hand, this 18th day of February, 1910.
